PAPER FEEDING MECHANISM

Hermann Otto Fischer and Frederic B. Fuller,
Springfield, Mass., assignors to Package Ma-
chinery Company, Springfield, Mass., a cor-
poration of Massachusetts

Application October 28, 1931. Serial No. 571,506

12 Claims. (Cl. 271—2.1)

This invention relates to sheet feeding devices, and has particular reference to devices in which successive sheets are forwarded to a predetermined location. One object of the invention is to improve prior devices of this character in respect to their quietness of operation. Another object is to provide grippers which engage the sheet near its forward edge only and do not return to their initial position through the path of the paper just delivered. Another object is the improvement of devices of this character by the elimination of mechanically actuated grippers. Another object is the provision of a simple and effective means for varying the terminal location to which the sheets are fed. A further object is to provide a sheet feed capable of operation upon sheets cut from the leading end of a continuous web, in which both the length of sheet and its terminal position can be varied at will. Additional objects will appear from the following description and claims.

Referring to the drawings;

Fig. 1 is a side elevation of the web feeding end of my improved device;

Fig. 2 is a similar view looking from the opposite side;

Fig. 3 is a detail;

Fig. 4 is a longitudinal section through the web feeding and sheet delivering mechanism;

Fig. 5 is a section on line 5—5 of Fig. 4;

Fig. 6 is a section on line 6—6 of Fig. 4; and

Fig. 7 is an enlarged detail of parts shown in Fig. 4.

The paper feed is designed to cut individual wrapping sheets from a roll of paper, cellophane, or other wrapping material, and to forward the cut sheets into the desired registration position such for example as a position directly above an article which is to be wrapped by suitable mechanism. The entire paper feed mechanism is supported on a sub-frame 10 which is attached to the main frame 11 by bolts 12. A roll of paper 13 is mounted upon a cross shaft 14 rotatable in open top journal boxes 15. From the roll the paper web 16 is drawn over a steel roll 17 fixed on a cross shaft 18, passing in its way under a tension roll 19 mounted on arms 20 subjected to a steady torque by a spring 21, as shown in Fig. 2. A cork surfaced roll 22 is spring-pressed down upon the roll 17 to give a positive grip to the paper. A lever 23 having a cam surface 24 may be provided to lift the shaft of the cork roll when it is desired to insert the leading end of a new web.

The roll 17 is driven by a ratchet mechanism permitting very fine adjustment of the length of

paper fed at each cycle. For this purpose one end of the shaft is surrounding by a free sleeve 25 (Fig. 3) having a pinion 26 (Fig. 2) fixed to it, the pinion meshing with a rack 27 reciprocable in a guide 28 pivoted about the sleeve. The lower end of the rack 27 is connected to a block 29 adjustably secured by a bolt 30 upon the rod-like end 31 of a bell-crank lever 32 pivoted to the sub-frame at 33. The other end of the bell-crank is slotted as at 34 to receive a crank 35 fast upon the end of the main paper feed drive shaft 36. Secured to the sleeve 25 is the outer member 37 (Fig. 3) of a ball ratchet or free wheeling unit, the inner member 38 of which is fixed to the shaft. This construction permits the adjustment of the length of paper fed at each cycle to any desired degree of fineness, by changing the position of the block, instead of having the adjustment limited to multiples of the pitch of the ratchet teeth as in prior constructions. It has the further advantage of being noiseless in action. The shaft 36 is driven continuously during the operation of the paper feed. As the roll 17 rotates, the roll 22 is rotated at an equal peripheral speed by means of the usual connecting gears.

After the paper web leaves the rolls 17, 22, it passes under a vertically reciprocable knife 40 which may be standard in its detailed construction and is, therefore, not described in detail. The knife is actuated at intervals by arms 41 on a shaft 42, which push the knife downwardly against the action of springs to sever the paper. Shaft 42 has an arm 43 to which is coupled a link 44 formed at its lower end to straddle the shaft 36. A cam roll 45 on the link rides upon a cam 46 secured to the shaft.

The shaft 42 also bears an arm 47 having at its free end a pin 48 passing into a slot 49 in one end of an arm 50. This arm is formed as a semi-circular brake band encircling a drum 51 on the roll shaft 18. A second semi-circular brake band 52 is joined to the first by springs 53, so that a constant restraint is placed upon the rotation of roll 17, preventing any tendency to overrun. In addition to this action, a slight backward motion of the roll 17 is given by the arm 47 at each elevation of the paper knife, the slot 49 permitting the knife to descend without effect on the roll. The backward rotation of the roll is allowed because of the ball ratchet which joins it to the operating mechanism. This short reverse rotation after the completion of the cutting operation is of value in freeing the paper from the knife, a tendency to stick being sometimes bothersome in the case of wax-treated paper webs.

As the paper is projected past the knife by the intermittently operated feed rolls, the leading end of the web is projected between lower and upper sets of belts 60 and 61 (Figs. 4 and 5). These belts 5 are not arranged in pairs but are staggered, there being two upper belts offset from the three lower ones. The lower belts pass around pulleys 62 on a shaft 63, around guide pulleys 64 loose on a shaft 65, and around pulleys 66 on a shaft held in arms 10 67 adjustably secured by clamp bolts to a rod 68. The shaft 63 is provided with a gear 69 (Fig. 2) meshing with a gear 70 on the paper feed drive shaft 36. The upper belts 61 pass around rolls 71 fixed on a shaft 72, around idlers 73 mounted 15 on arms 74 adjustably mounted on a rod 75, and around adjusting rolls 76 and terminal rolls 77, the two latter rolls 76 and 77 being mounted on opposite ends of a slide 78 adjustably secured by bolts 79 to a portion of the main frame. The slide also 20 has shoe portions 80 which rest upon the upper surfaces of the lower runs of the belts 61 to provide a backing against which pressure may be exerted by the paper-carrying pads. The rolls 76 and 77, being mounted on the same slide, move 25 back and forth with the slide so that their position can be varied without affecting the length of the belts. The shaft 72 is provided with a gear 80' meshing with a gear 81 on the shaft 65 previously referred to.

30 Situated directly below the belts are a pair of chains 82 running around sprockets 83 and 84. The sprockets 83 are secured to the shaft 65 and the sprockets 84 to an idle shaft 85. Attached to 35 each chain are a plurality (two as shown) of pads 86 pivotally attached at 87 to clips 88 secured in the links of the chain. A flat spring 89 is secured to the pad and presses against the chain to urge the paper-contacting surface 90 of the pad outwardly.

40 The operation of the sheet-delivering mechanism will now be described. As the feed rolls 17 and 22 first start to rotate at the beginning of a cycle, the leading end of the paper web is fed first past the knife 40 and then between the 45 staggered belts 60 and 61. These belts are continuously rotating, but due to their staggered relation they do not grip the paper. Rather do they exert what may be called a stroking action on the paper, exerting enough friction to keep 50 the leading end of the web extended beyond the knife. The belts, and also the pads 86, move at a constant speed which is preferably greater than the maximum speed with which the leading end of the web is projected by the feed rollers, 55 so that the paper is kept smooth and is prevented from piling up. The speed with which the web is projected may vary, but whether it is being fed out at a constant speed or is accelerating or decelerating does not change the manner in 60 which the belts and pads operate upon it. When the paper feed rolls stop, the forward movement of the web of course stops also; while the belts continue to move at their same steady rate, slipping over the extended end of the web until it 65 is cut off by the action of the knife. During this same period a pair of pads 86 (one on each chain 82) are carried around the sprockets 83 so that their surfaces 90 press the web against the under surfaces of the belts 61. Here again 70 the pressure is not great enough to prevent slipping of the continuously moving pads while the end of the web is held stationary, but is merely sufficient to hold and carry the cut sheet after severance. At the time when the knife is actuated, 75 the pads are adjacent the leading end of

the web, the chains being adjusted as will be described below to the proper timing for the size of the sheet to be cut.

At the instant of severance, the cut sheet is held between the belts 60 and 61 and between the belts 61 and the pads 86. Both sets of belts and the chains 82 move with the same constant surface speed. It will be noted that the upper set of belts 61 and the chains extend beyond the lower belts, support of the under surface of the cut sheet (held by the pads at its front edge only) being assumed by guide members 91 and a plate 92 as soon as the sheet passes beyond the range of belts 60. The termination of the feeding action of the pads is brought about merely by their running beyond the point where belts 61 curve up around their terminal pulleys 77. A paper stop 93 is secured to the slide 78 to check the momentum of the traveling sheet and to insure that it comes to rest in a definite location.

Adjustment of the paper feed for sheets of different length is accomplished by three adjustments. The length of sheet to be cut is determined solely by the amount of rotation given at each cycle to the feed rolls 17 and 22, a matter 100 governed by the position of the block 29. The knife always operates at the same point in the machine cycle. When the length of sheet is varied, however, it is generally desirable to center it with respect to the delivery point, which requires an adjustment of the point to which the edge of the cut sheet is delivered by the pads. As pointed out above, this is accomplished merely by shifting the slide 78, which varies the position of roll 77 and hence the point at which the 110 tractive power of the pads ends, and at the same time varies the position of the paper stop 93.

One further adjustment is necessitated by the desirability of having the pads 86 adjacent the leading end of the cut sheet during its travel. It 115 will be recalled that the end of the web is projected past the knife by the intermittent feed rolls and is then held stationary in the interval between the stoppage of the rolls and the actuation of the knife, the pads meanwhile slipping over the paper. With different lengths of sheet 120 it will be obvious that the pads need to be in different positions at the time the knife cuts. Provision for this is found in the drive for the shaft 65. A split sleeve 100 surrounds the shaft 125 and projects with it through the frame 10. Upon this sleeve within the frame is fixed a gear 101 meshing with the gear 70 previously mentioned. A clamp 102 is mounted on the sleeve outside the frame so that it can be secured to the shaft in 130 any angular position desired. By loosening this clamp, the chains 82 can be shifted so as to bring the pads into proper registration with the end of the web at the instant of cut, this registration being preserved for further cycles by tightening the clamp.

The continuously traveling chains 82 are of such overall length that a pad 86 is brought into operative position at each cycle of the machine. In the case shown, there are two pads on each chain, so that the chains make one-half of a complete turn at each cycle. While the chains move constantly the initial feeding of the web is intermittent. Considering the chains as set by the adjustment just described for one size of 140 sheet, the movement of a pad up to edge gripping position from a position 180° away may be considered in two sections, although in actuality there is no interruption to the pad's continuous motion. During the first section of this move- 145

- ment the web 16 is stationary, the web feeding rotation of rolls 17 and 22 not yet having started. During the next section the leading end of the web 16 is being projected beyond the cutter 40 by the action of the feed rollers, the pads meanwhile slipping freely over the web. Since the feeding movement of the web is independent of the cyclic travel of the pads it is possible to vary the amount that the web is projected beyond the cutter by changing the adjustment 29 without producing any corresponding change in the timing of the pads. Without such a change, however, the pad would be in different positions with respect to the leading edge of the web at the instant of cut. By means of the adjustment 100, 102, it is possible to shift the pads so that they fall at the leading edge of the web when it is severed. This produces no change in the ultimate position in which the severed sheet is dropped, since that position depends upon the adjustment of the terminal pulleys 77 and not upon the adjustment of the chains 82. The projection of the chains beyond the terminal pulleys is purely idle, and may be made any amount necessary to give 25 the correct total length of chain to produce the spacing of pads required.
- The invention can be put into practice with various forms of mechanism, that shown being preferred. The arrangement and design of the various parts will depend upon the use to which the feeding mechanism is to be put, and the invention is, therefore, not to be limited to the specific form shown. The pads operate on the sheet to grip and release it entirely without noise, and without the necessity for tripping devices necessarily employed where mechanically actuated grippers are used. Furthermore, the gripping members do not return to their initial position through the path of the sheet which they have just delivered, but continue their uninterrupted motion back to their starting point without the necessity of waiting for the sheet just delivered to be removed. This greatly speeds up the operation of the device, particularly as a plurality of pads may be provided following each other in endless succession.
- I claim:
1. A sheet feeding device comprising spaced supporting pulleys, a continuously moving endless conveyer passing around the pulleys, a second continuously moving conveyer opposed to the first and extending beyond the terminal supporting pulley thereof, and a pad on the second conveyer engaging the sheet adjacent its leading edge only by pressing it against the first conveyer and terminating its engagement with the sheet by passing beyond said terminal supporting pulley.
  2. A sheet feeding device comprising a continuously moving conveyer having a straight run terminated by a supporting pulley, a second continuously moving conveyer opposed to the first and extending beyond the terminal supporting pulley, and a pad on the second conveyer adapted to engage a sheet adjacent its leading edge only by pressing it against the first conveyer and to carry the sheet forward until released by the passage of the first conveyer around the terminal supporting pulley.
  3. A sheet feeding device comprising a continuously moving conveyer having a straight run terminated by a supporting pulley, a second continuously moving conveyer opposed to the first and extending beyond the terminal supporting pulley, a pad on the second conveyer adapted to engage a sheet by pressing it against the first
- conveyer and to carry the sheet forward until released by the passage of the first conveyer around the terminal supporting pulley, and a paper stop extending into the path of the paper beyond the terminal supporting pulley to prevent it from overrunning. 80
4. A sheet feeding device comprising a continuously moving conveyer having an active run terminated by a supporting pulley, a second continuously moving conveyer opposed to the active run of the first and extending beyond the terminal supporting pulley, a pad on the second conveyer adapted to engage a sheet by pressing it against the first conveyer and to carry the sheet forward by such contact until released by the passage of the first conveyer around the terminal supporting pulley, and means to adjust the position of said terminal supporting pulley to vary the position to which the sheet is fed. 85
  5. A sheet feeding device comprising a continuously moving endless conveyer having an active run bounded by a fixed pulley and a terminal pulley, and an inactive run bounded by said pulleys and having a reverse bend formed by an idle pulley and an adjusting pulley, the adjusting pulley being nearer the fixed pulley than is the idle pulley, a second conveyer opposed to the active run of the first and extending beyond the terminal pulley, a pad on the second conveyer adapted to engage a sheet by pressing it against the first conveyer and to carry the sheet forward by such contact until released by the passage of the first conveyer around the terminal pulley, a common support for the terminal and adjusting pulley, and means to hold said support in different positions to vary the position of the terminal pulley without varying the length of the first conveyer. 90
  6. A sheet feeding device comprising two opposed sets of staggered continuously running belts, one extending beyond the other, pulleys supporting the belts, intermittently operable means for feeding the leading end of a wrapper web between the staggered belts, a continuously running conveyer opposing and in line with the longer of the two sets of staggered belts and extending beyond the terminal supporting pulley thereof, one or more pads on said conveyer engaging the leading edge of the projected end of the wrapper web and pressing it frictionally against that one of the belts with which it is in line, so that upon severance of the web after the pads have reached a point adjacent its leading edge the severed sheet will be carried by the engagement between the pads and the mating belts 120 until the pads pass beyond the terminal pulley of the latter. 110
  7. A sheet feeding device comprising a continuously moving conveyor presenting a sheet engaging surface, a second continuously movable conveyor opposed to the first, and one or more pads on the second conveyor positioned to press the leading edge of a sheet only against the first conveyor to cause the sheet to be fed forwardly by the two conveyors. 135
  8. A sheet feeding device comprising a continuously moving endless conveyor presenting a sheet engaging surface, a second continuously movable endless conveyor opposed to the first, one or more pads on the second conveyor spring pressed against the first conveyor, and intermittently operable devices to project the leading edge of a sheet into the bite of the two conveyors and to hold it in that position until the sheet is gripped 150

adjacent its leading edge by the first conveyor and a pad on the second conveyor.

9. A sheet feeding device comprising two opposed sets of staggered continuously running belts, one extending beyond the other, pulleys supporting the belts, an intermittently operable device for feeding the leading end of the sheet between the staggered belts and for holding it while the belts slip over it to give it an initial support, a continuously running conveyor opposing and in line with the longer of the two sets of staggered belts and extending beyond the terminal supporting pulley thereof, a pad on said conveyor engaging the leading end of the projecting sheet, pressing it frictionally against that one of the belts with which it is in line, and slipping over the sheet until the latter is released, and means for releasing the sheet so that it may be moved by the frictional grip between the pad and its mating belt, and will be deposited by the passage of the pad beyond the terminal supporting pulley of said belt.

10. A sheet feeding device comprising a continuously moving endless conveyer presenting a sheet engaging surface, a second continuously moving endless conveyer opposed to the first, one or more pads on the second conveyer yieldably pressed against the first conveyer, and devices operable to project the leading edge of a sheet into the bite of the two conveyers at a lower surface speed than that of the conveyers and to release the sheet when it is gripped adjacent its leading edge by the first conveyer and a pad on the second conveyer.

35. 11. A sheet feeding device comprising two opposed sets of staggered continuously running belts, one extending beyond the other, pulleys

supporting the belts, devices operable to project the leading end of a sheet into the bite of the two sets of belts at a lower rate of surface speed than that of the belts, so that the belts slip over it to give it an initial support, a continuously running conveyer opposing and in line with the longer of the two sets of staggered belts and extending beyond the terminal supporting pulley thereof, a pad on said conveyer engaging the projecting end of the sheet, pressing it frictionally against that one of the belts with which it is in line, and slipping over the sheet until the latter is released, and means for releasing the sheet so that it may be moved by the frictional grip between the pad and its mating belt, and will be deposited by the passage of the pad beyond the terminal supporting pulley of said belt.

12. A sheet feeding device comprising spaced supporting pulleys, a continuously moving endless conveyer passing around the pulleys, a second continuously moving conveyer opposed to the first and extending beyond the terminal supporting pulley thereof, a pad on the second conveyer engaging the sheet by pressing it against the first conveyer and terminating its engagement with the sheet by passing beyond said terminal supporting pulley, and devices operable to project the leading edge of a sheet into the bite of the two conveyers at a lower surface speed than that of the conveyers and to release the sheet when it is gripped adjacent its leading edge by the first conveyer and a pad on the second conveyer.
